US00D912061S

(12) **United States Design Patent** (10) **Patent No.:** **US D912,061 S**
(45) **Date of Patent:** **** Mar. 2, 2021**

(54) **LATTICE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Chowdhury**, San Francisco, CA (US); **Markus Diebel**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Joe Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/693,579**

(22) Filed: **Jun. 3, 2019**

(51) LOC (13) Cl. **14-02**

(52) U.S. Cl. **D14/440**
USPC **D14/440**

(57) **CLAIM**

The ornamental design for an lattice, as shown and described.

DESCRIPTION

FIG. 1 is a right perspective view a lattice showing our new design;

FIG. 2 is a front perspective view thereof; and,

FIG. 3 is a left perspective view thereof.

(Continued)

The dashed broken lines illustrate boundaries of the lattice which form no part of the claimed design.
